UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed May 11, 1922. Serial No. 560,031.

To all whom it may concern:

Be it known that I, JESSE A. B. SMITH, a citizen of the United States, residing in Stamford, in the county of Fairfield and State of Connecticut, have invented certain new and useful Improvements in Type-writing Machines, of which the following is a specification.

The present invention relates to continuous billing typewriting machines, one form 10 of which machine is shown in the patent to Wernery and Smith, No. 1,132,055, granted March 16, 1915.

In a machine of this type, work-sheets 15 or webs are used in several layers or plies, each provided with printed forms constituting one piece of work, which, when completed, may be torn from the continuous web. Carbon-sheets interleaved between 20 the webs or plies are mounted on a carbon-carriage, so as to advance with the web toward the platen while typewriting, and so as to be drawn back by the carbon-carriage into the succeeding form-section of 25 the web, after the leading form-section has been typed, and prior to detachment from the web of such leading form-section. In conjunction with such individual-form-webs, record-sheets are often employed, upon 30 which record-sheets the writings on the individual forms are accumulated and condensed as the filling in of the forms progresses; and, to provide for this condensation, the record-sheets are ordinarily held 35 against movement while the form-webs are advanced for the detachment of a form which has been filled in and for the positioning of the succeeding form. These record-sheets have heretofore been individual sheets, replaceable when filled. For 40 convenience, the form-webs are preferably led from web-holders on a cabinet at the rear of the typewriter-stand; over the rear of the stand; to a carbon-holder on a table 45 connected to the rear of the typewriting machine, and thence down and around the platen in the usual manner.

A feature of the invention is the provision of a take-up device for the written 50 portion of a record-sheet, fed to and from the platen in the form of a continuous web so as to be of a length such that the above-referred to, comparatively frequent, replacements are unnecessary. A feature of the 55 invention is the adaptability of the take-up

device to use in conjunction with webs other than a record-web. For instance, instead of detaching sections from the form-webs as the same are written, the present take-up device may be used to gather up and hold the form-webs until such time as may be desired to separate and use the individual forms.

A further feature of the invention is the provision of means whereby the web-take-up 60 device, preferably located out of the way of the operator, at the rear of the typewriter-stand, may be actuated by the operator from the latter's position at the front of the stand; and, in this connection, a feature of the invention is a take-up device and means for feeding the written portion of the web thereto such that constant attention thereto by the operator is unnecessary; the take-up device being operable at will; 65 and at convenient intervals only, and the web feeding and guiding apparatus being such that the written part of the web may be allowed to accumulate as a slack on the floor or elsewhere until such time as it 70 may be convenient for the operator to gather the same into the take-up device.

A feature of the invention is the provision of means whereby a record-sheet in the 75 form of a web may be fed, in superposed relation to individual-form-webs, to the platen by the usual line-space movement of the platen, but which may be held against movement while the other webs are moved for the detachment and placement of the 80 successive sections thereof; and the provision of means whereby the written portion of the record-web may be diverted from the other webs, thence to be led to the take-up 85 device.

In the preferred form of the invention, a cabinet such as ordinarily contains individual-form web-holders at the rear of the typewriter-stand also contains a supply roll or holder for the record-web and 90 the take-up device or roll for the latter, and there is provided an actuating connection extending under the typewriter-stand from the take-up device, carrying a pedal, by means of which the take-up device may 95 be actuated by the operator's foot.

Other features and advantages will hereinafter appear.

In the accompanying drawings, Figure 1 is a view in side elevation of the 100 110

web-cabinet, typewriter-stand and record-sheet pick-up device; the typewriter being indicated on top of the stand with the webs connected thereto.

5 Figure 2 is a view in side elevation, partly cross-sectional, of the platen-frame, platen and certain associated devices shown in their normal or printing positions thereon.

10 Figure 3 is a detail view showing the record-sheet pick-up device and connections thereto and the actuating device therefor.

15 Referring to the drawings, the typewriter-stand is indicated by a top or table piece 1, uprights 2 and suitable braces 3. It will be understood that the stand or desk may be of any style which permits feed of the webs from the rear thereof to the typewriter.

20 The typewriter 4 is indicated in dotted lines on the stand. The particular style of typewriter, here intended to be shown in illustration of the invention, is that disclosed in United States Letters Patent to Fortin, No. 1,237,319, of August 21, 1917, of which the carriage of the typewriting machine has attached thereto a rearward extending table 5, on which a carbon-holder 6 is adapted to move with the carbons and webs toward the platen 8 as the carbons and webs have their line-feed movements around 25 the platen, and which is adapted to be moved backward with the carbons to draw the carbons into successive web-sections after the leading web-section has passed around the platen. It is unnecessary here to describe in 30 detail the structure of the table on which the carbon-holder operates, reference being made to the aforesaid Fortin patent for such description thereof as may be desired. Suffice here to say that the carbon-holder of 35 the Fortin patent comprises a plate 7, having secured thereto a number of clips (not shown), each of which clips engages and holds the rear end of a carbon-sheet, the several clips being stepped up one from another 40 more conveniently to enter and slide between the superposed web-pieces.

45 In the Fortin patent, a single fan-fold web is shown; the superposed fan-folded sheets or strips forming the web each being composed of detachable units bearing the same individual form or blank. Instead of a single web comprised of fan-folded superposed strips or sheets, several single strips or webs, as illustrated in Figure 1 of the present application, may be employed; each of the superposed webs being composed of detachable units bearing the same form or blank.

50 As shown in the aforesaid Fortin patent, the carbon-holding plate 7, with the carbons attached thereto, interleaved with the webs, is detachably secured to a carriage 9, which moves therewith on the table 5 to and from the platen, as above described. This de- 55 tachability of the carbon-holders permits the

same to be interchanged; that is to say, permits a carbon-holder, with carbons interleaved with webs comprising forms of one character, to be substituted for another carbon-holder, with attached carbons and webs comprising forms of another character; thus avoiding the necessity, at the time of substituting webs of one form for webs of another form in the machine, of interleaving the webs bearing the desired forms with a set of carbons and attaching the latter to the carbon-holder. In other words, the webs of each set or style of individual form, which the operator may be called upon to use, have their carbons interleaved therewith and attached to one of the several carbon-holders. The carbon-holder of the selected web-form is then substituted for the carbon-holder for the web-form which may be in the machine. 85

60 In a fan-fold machine such as described, the platen is lifted after the printing of each individual form or length of the webs, so that the webs may be freely and horizontally drawn forward to position another section thereof with respect to the platen. At this time the record-sheet is clamped against movement so that the writings which appear perhaps at a small part only 65 of the individual forms may follow each other on the record-sheet without the intervening spaces, which, on the webs, are occupied by printed headings and other matter not wanted on the record-sheet. In other words, the writings on the record- 70 sheet are condensed, and the clamping of the record-sheet, when the individual form webs are drawn forward, is to eliminate the unnecessary spacings on the record-sheet referred to. Normally the platen is locked 75 in printing position and the record-sheet clamp is held clear of the record-sheet. These features, which are well-known in the art, will now be described only in so far as may be desirable for a clear understanding 80 of the present invention. 100

85 Referring to Figure 2, the platen 8 is shown as revolvably mounted on an axle 10 carried at each end in an arm 11 pivoted at 12 to the platen-frame 13. On the 90 frame 13 is the usual paper-guide and apron 14; and on the frame 13 at the rear of the same are brackets 5^a, which support the forward cross-piece 5^b of the table 5, hereinbefore referred to. When the platen 95 is in printing position, as shown in Figure 2, the usual front and rear pressure feed-rolls 15 and 16 engage the same through openings in the apron 14. The arms 11, by 100 means of which the platen is swung up and down between its printing station and its web-positioning station, form part of a frame which is extended, as indicated at 17, to the rear of the platen. To this swinging frame 17 is attached a paper-table 18 105

and a gage-piece 19 having a slidably-adjustable gage 20 thereon, to which slidable gage the leading ends of the webs may be drawn preliminary to detachment of the 5 leading web-section. The swinging frame also carries a knife 21 against which the typewritten web-sections may be drawn to sever the same from the webs. The swinging frame 17, when the same is in printing 10 position, rests at its rear upon a shaft 22, which has its bearings in the frame 13.

The swinging platen frame is locked down in printing position by means of hooks 23 on arms 24, which arms are fast to the shaft 22; 15 the shaft 22 being a rock-shaft. For engagement by the hooks 23, the side pieces of the swinging frame 17 each have a pin 25 over which the hooks 23 snap when the swinging frame has been dropped by gravity to its 20 position of rest on the shaft 22. The hooks 23 are snapped into locking position by means of a spring, not shown, but which is preferably coiled on the shaft 22. One of the arms 24 is extended, as indicated at 26, to 25 carry a finger-piece 27 by means of which the hooks may be swung rearward out of engagement with the pins 25 to permit the swinging platen-frame to be lifted when a new section of web is to be positioned. The 30 swinging frame 17 may be lifted by drawing on the upper edge 28 of the table 18, which is fast thereto.

In Figure 2 three plies of web are shown at 29, 30 and 31 with carbons 32 interleaved therewith. The record-sheet is indicated at 33 as the sheet immediately in engagement with the platen, and as having one of the carbons 32 faced thereto. The web-sheets 29, 30 and 31 are shown at their leading ends 40 in front of the table 18; whereas the leading end 34 of the record-sheet is led under the forward edge of the table 18 and to the rear thereof.

When the platen is swung up to permit 45 the webs to be drawn forward for the positioning of another section thereof, the record-sheet is clamped against the inner face of a cross-piece 35, which carries the table 18, by means of a bar 36 supported at each 50 end by a lever 37, the levers 37 being pivoted at 38 to the swinging frame 17. The levers 37 are extended to the rear of the pivots 38, and are then bent forward to their distal ends 39 where each carries a roller 40 55 adapted to bear against the nose 41 of the corresponding hook 23. Springs 42, coiled around the pivots 38 of the clamp-carrying levers 37, urge these levers in such direction as to cause the rolls 40 to bear against the 60 noses of the hooks 23. When the arm 26 is in its Figure 2 position, with the hooks 23 in engagement with the pins 25 to hold down the swinging frame, the noses 41 of the hooks 23 prevent the springs 42 from 65 throwing the clamping bar 36 forward to

clamp the record-sheet. When, however, the hook-releasing arm 26 is thrown rearward to release the swinging platen-frame, the clamp-levers 37, acting under the influence of the springs 42, follow the hooks 23, 70 and, in so doing, rock around their pivots 38 in such manner as to cause the bar 36 to clamp and hold the record-sheet 34 against the cross-piece 35 of the swinging frame. In order that, if desired, the clamp may be released from the record-sheet 34, whatever the position of the arm 26, there is attached to one of the clamp-levers 37 a finger-piece 43, by means of which the clamp-levers may be rocked counter-clockwise on their pivots 38, 80 removing the roll 40 from the arm 26 and removing the clamp 36 from the cross-piece 35.

Referring to Figure 1, the webs 29, 30 and 31 are shown as led from supply-rolls 44, 45 and 46, respectively, revolvably mounted on arms 47 carried by right and left-hand standards 48 on a base-piece 49 forming a cabinet at the rear of the typewriter-stand. The base-piece 49 of the cabinet may be perforated, as at 50, to receive the rear feet of the stand, to cause the cabinet to be properly positioned and centered with respect to the stand. The record-sheet 33 is drawn from a supply-roll 51 revolvably mounted on arms 52 projecting forwardly from the standards 48. The webs and the record-sheet are led from their respective supply-rolls over a cross-rod 53 which connects the standards 48 at the top thereof. Preferably another cross-rod 54 connects the standards above the cross-piece 53. The webs and record-sheet pass loosely between the rods 53 and 54; but the rod 54 controls the sheets in such way that the slack in the sheets is formed forward of the standards 48 instead of to the rear 105 thereof.

The leading portion of the record-sheet, indicated in Figure 2 at 34 as passing backward from the platen over the table to the rear thereof, is shown in Figure 1 as dropping rearward to the floor at 55, where it may be allowed to accumulate. This leading end is, however, finally connected to a pick-up roll 56 revolvably mounted at 57 on arms 58 carried by and projecting rearward from the standards 48 below the web supply-rolls.

For rotating the pick-up roll 56 as and whenever desired, to gather up the accumulated record-sheet, there is pivotally mounted on the axle 57 of the pick-up roll an arm 59 which carries a pawl 60 urged by a spring 60^a, into engagement with a ratchet-wheel 61 fast to the axle of the pick-up spool or roll. The arm 59 is pivotally connected at 62 to a link 63 which extends forward and is pivotally connected at 64 to one arm 65 of a bell-crank lever, pivoted at 66 to brackets on the base-piece 49 of the roll cabinet. The forward arm 67 of this bell-crank carries a pedal 68, which the typist 130

may operate with his foot. Upon each depression of the pedal 68, the pawl and ratchet 60-61, acting on the pick-up roll, effects a partial rotation of that roll; and, 5 after each depression of the pedal, a spring 69, attached at one end to the arm 65 of the bell-crank lever and at its other end to the cabinet base-piece 49, returns the pedal and the pawl-carrying arm 59 to normal positions. A leaf-spring 70, secured at 71 to one of the arms 58 which support the record-sheet pick-up roll, bears against the face of one of the disks or end plates of the pick-up roll to serve as a brake to prevent the 10 overthrow of the roll under the action of the foot device, and to prevent rotation of the roll in the other direction, such as would unwrap the record-sheet therefrom.

In the structure hereinbefore described, 20 it is the typewritten portion of the record-sheet to which the pick-up device is applied. It is obvious, however, that the pick-up device might be used for any web fed to and from the platen. For instance, instead of 25 severing the individual forms from the webs 29, 30 and 31, after the same have been typewritten, these webs might be fed unbroken to a pick-up device such as shown, which latter would then serve as a store until such 30 time as it might be desired to sever and use the individual forms.

Variations may be resorted to within the scope of the invention, and portions of the improvements may be used without others.

35 Having thus described my invention, I claim:

1. The combination with a typewriting machine and stand therefor; of a web-holder; means for feeding the web from the 40 holder to the platen; a pick-up roll for the typewritten portion of the web, mounted near the floor and at a sufficient distance below the typewriting machine to permit relative travel of the machine-carriage and 45 the pick-up roll without fouling the web; and a foot-controlled device for intermittently and at will rotating the pick-up roll.

2. The combination with a typewriting machine and stand therefor; of a web-holder; means for feeding the web from the 50 holder to the platen; a pick-up roll for the typewritten portion of the web, mounted near the floor and at a sufficient distance below the typewriting machine to permit relative travel of the machine-carriage and 55 the pick-up roll without fouling the web; a pawl-and-ratchet mechanism for effecting rotation of the pick-up roll; and a pedal for actuating the pawl-and-ratchet mechanism.

60 3. The combination with a typewriting machine and stand therefor; of a web-holder; means for feeding the web from the holder to the platen; a pick-up roll for the typewritten portion of the web, mounted 65 near the floor and at a sufficient distance be-

low the typewriting machine to permit relative travel of the machine-carriage and the pick-up roll without fouling the web; a pawl-and-ratchet mechanism for effecting rotation of the pick-up roll; a link extending 70 forward from the pawl-and-ratchet mechanism to a position under the typewriter-stand; and foot-controlled means for vibrating the link to operate the pawl-and-ratchet mechanism.

4. The combination with a typewriting machine and stand therefor; of a web-holder; means for feeding the web from the holder to the platen; a pick-up roll for the typewritten portion of the web, mounted 80 near the floor and at a sufficient distance below the typewriting machine to permit relative travel of the machine-carriage and the pick-up roll without fouling the web; a pawl-and-ratchet mechanism for effecting 85 rotation of the pick-up roll; a link extending forward from the pawl-and-ratchet mechanism to a position under the typewriter-stand; and a bell-crank lever connected to the link and having a pedal thereon 90 for vibrating the link to operate the pawl-and-ratchet mechanism.

5. The combination with a typewriter-stand and a continuous billing typewriting machine thereon having a carriage-extension movable with the carriage, and a carbon-carrier movable on the carriage-extension toward and from the platen; of a web-holder, means for feeding the web from the holder to the platen, a stationary pick-up 100 device or accumulator for the typewritten portion of the web, supported independently of the machine and a substantial distance below it so that a stretch of web will be provided beyond the rear of the carriage-extension to permit travel of the carriage-extension and the carbon-carrier relatively 105 to the pick-up device without fouling the web, and means for operating the pick-up device at will comprising a pedal under the 110 typewriter-stand and connections from the pedal to the pick-up device.

6. The combination with a typewriter-stand and a continuous billing typewriting machine thereon having a carriage-extension 115 movable with the carriage, and a carbon-carrier movable on the carriage-extension toward and from the platen; of a web-holder, means for feeding the web from the holder to the platen, a pick-up device or ac- 120 cumulator for the typewritten portion of the web located a sufficient distance from the machine to permit play of the web beyond the carriage-extension so as to avoid fouling of the web by the movements of the carriage-extension and the carbon-carrier relatively to the pick-up device, and means for operating the pick-up device arranged to allow an accumulation of the web as a slack between the platen and the pick-up 125 130

device until such time as it may be desired to gather the slack into the pick-up device by actuation of the latter.

7. In combination, a typewriter-stand, a continuous billing typewriting machine thereon having a carriage-extension movable with the carriage, a carbon-carrier movable on the carriage-extension to withdraw the carbons from between the typed work-web sections, means for separating the innermost work-web from the others beyond the platen, and means for severing the webs thus separated from the innermost web, a pick-up device beyond the rear of the carriage-extension to which the typewritten portion of the unsevered innermost web is connected, and means for actuating such pick-up device.

8. In combination, a typewriter-stand, a continuous billing typewriting machine thereon having a carriage-extension movable with the carriage, a carbon-carrier movable on the carriage-extension to withdraw the carbons from between the typed work-web sections, means for separating the innermost of the webs from the others beyond the platen, and means for enabling the work-webs other than the innermost web to have movement to the platen relative to the innermost web, a pick-up device to which the typewritten portion of the innermost web is connected beyond the rear of the carriage-extension, and means operable independently of the movement of said other webs to the platen for actuating such pick-up device.

9. In combination, a typewriter-stand, a continuous billing typewriting machine thereon having a carriage-extension movable with the carriage, a carbon-carrier movable on the carriage-extension to shift the carbons from between the typed work-web sections, means for separating the innermost of the webs from the others beyond the platen, means for enabling the work-webs other than the innermost web to have intermittent movement to the platen relative to the innermost web, and means for holding the innermost web against movement while such intermittent movement of the other webs is effected, a pick-up de-

vice beyond and below the rear of the carriage-extension to which the typewritten portion of the innermost web is connected, and means operable independently of the movement of said other webs to the platen for actuating the pick-up device.

10. In combination, a typewriter-stand, a continuous billing typewriting machine thereon having a carriage-extension movable with the carriage, a carbon-carrier movable on the carriage-extension to withdraw the carbons from between the typed work-web sections, means for separating the innermost of the webs from the others beyond the platen, means for displacing the platen to permit an intermittent free movement of the webs other than the innermost web, and means for holding the innermost web against movement while such intermittent movement of the other webs is effected, a pick-up device beyond and below the rear of the carriage-extension to which the typewritten portion of the innermost web is connected, and means conveniently accessible to the operator seated at the machine for actuating such pick-up device.

11. In combination, a typewriter-stand, a continuous billing typewriting machine thereon having a carriage-extension movable with the carriage, a carbon-carrier movable on the carriage-extension to withdraw the carbons from between the typed work-web sections, means for separating the innermost of the webs from the others beyond the platen, means for displacing the platen to permit an intermittent free movement of the webs other than the innermost web, and means automatically effective upon such displacement of the platen to hold the innermost web against movement while such intermittent movement of the other webs is effected, a pick-up device beyond the rear of the carriage-extension to which the typewritten portion of the innermost web is connected, and means for actuating the pick-up device.

JESSE A. B. SMITH.
